UNITED STATES PATENT OFFICE.

WILLIAM B. GATEWOOD, OF HUNTINGTON, WEST VIRGINIA, AND VICTOR P. DALMAS,
OF ASHLAND, KENTUCKY.

METALLIC RAILWAY-TIE.

1,367,183.

Specification of Letters Patent. Patented Feb. 1, 1921.

Application filed November 8, 1919. Serial No. 336,617.

To all whom it may concern:

Be it known that we, WILLIAM B. GATEWOOD and VICTOR P. DALMAS, citizens of the United States, residing at Huntington, 5 in the county of Cabell and State of West Virginia, and Ashland, in the county of Boyd and State of Kentucky, respectively, have invented certain new and useful Improvements in Metallic Railway-Ties, of 10 which the following is a specification.

Our invention relates to metallic ties such as are used to hold railway rails, and it permits the rails to be held rigidly in position during all conditions of use, so that 15 the cars will be afforded a stable and even trackage.

More particularly, our invention relates to metallic ties for use in mines, factories, farms, plantations, construction work, and other places where the track has to be frequently shifted as the work progresses, and to means for providing a tie that can be quickly set in place and will provide a sure and positive holding means for the rails. 20

In the past, numbers of ties built of metallic material have been conceived, but in general the structure has been so complicated that it has been impractical to use them. The cost of manufacture has either 25 been prohibitive or the complicated structure has proved to be subject to breakage or wear, which necessitated a large outlay for maintenance. In some instances in the past art the holding clamp for the rail has been struck up from the body of the tie. This structure has proven to be expensive to construct where the holding clamp has been large enough to insure strength and where the clamp has been punched out of the body 30 of the tie proper, the tie itself has been weakened. In this later form the strength of the clamps themselves has, moreover, not proven sufficient to stand the strains of customary usage, and the clamp members 35 have been either broken off or bent.

There is another type of metallic tie where the rail fastening means consists of metallic clamping buttons with enlarged heads. The clamping buttons which grip the outside of 40 the rail base are fixed immovable, but those gripping the inner side of the rail base are pivoted so that the projections that engage the rail may be rotated out of engagement and the rail removed from the tie. The

clamping buttons have often proved too 55 frail to withstand continued usage and were frequently found to be broken or bent by the strains to which they were subjected. It was to overcome the disadvantages of the devices in use in the prior art that this invention was conceived. 60

An object of this invention is to provide a tie that embodies simplicity of construction with great strength. The holding clamp for the rail is formed integral with 65 the body of the tie itself, and by the simple process of bending the end of the tie to form a close fitting contact with the base of the rail. The rail is held on the other side by a revolving bar clamp that when swung into 70 place is held in engaging position against the rail base by means of the natural spring of the bar itself. Because of the great strength of the holding clamp, which consists of the struck-up end of the channel 75 beam forming the tie, this part of the rail fastening device is practically indestructible. The revolving bar clamp which forms the other part of the rail fastening device is very simple in construction. The only 80 part subject to any considerable degree of destructive wear is the rivet upon which the bar is pivoted. The repair of this rivet is an inexpensive operation which may be performed in any forge shop, and the tie is 85 again ready for use in a short space of time.

Another object of this invention is to provide a tie that can be quickly and facilely fastened in place with the only necessary tools consisting of a sledge, crowbar, pick, 90 or other heavy body. These tools are always at hand in a mine or in any construction work, and this feature of our device insures that no time will be lost in laying the track for the cars. Because the tie is constructed of a section of channel beam the 95 up-struck sides of which are designed to engage with the earth, the creeping of the tie is prevented.

With these and other objects in view, 100 which may be incident to the use of the improvements, the invention consists in the parts and combinations thereof hereinafter set forth and claimed, with the understanding that the several necessary elements constituting the same may be varied in proportions and arrangement without departing 105 from the spirit and scope of the invention.

In order to make the invention more clearly understood, we have shown, in the accompanying drawings, means for carrying the same into practical effect without limiting the improvements in their useful applications to the particular constructions which, for the purpose of explanation, have been made the subject of illustration.

Figure 1 is a side elevation of one form 10 of a metallic tie embodying our invention;

Fig. 2 is a top plan view of the tie shown in Fig. 1;

Fig. 3 is a bottom plan view of a modification of the tie shown in Figs. 1 and 2; and

Fig. 4 is a cross section taken on line 4-4 of Fig. 1, showing the channel beam construction of the tie body and of the holding clamp.

Referring to Figs. 1 and 2, 1 indicates a tie body of metal formed in substantially 20 channel beam shape with struck up edges 2 and 3, as plainly shown in Fig. 4. The supporting body of the tie comprises this piece, which, in use is designed to be turned so 25 that the struck up edges 2 and 3 will be on the bottom side, and will become embedded in the dirt by reason of the pressure of the weight of the track and of the passage of cars over the rails. These edges prevent the 30 movement of the tie in the direction of the track.

The ends of the tie body are bent up by means of a die press or any other suitable 35 means to form holding clamps 4. These holding clamps are accurately constructed to fit the outside rail bases 5 of the rails 6. By reason of the accurate fit of the holding clamps to the rail bases it is unnecessary 40 to have any wedge or block of wood or iron fitted between these members, as has often been the practice in the prior art. The channel beam shape of the tie body gives great strength to the holding clamps 4 and practically insures them against bending or dis- 45 torsion in ordinary use.

The inside rail bases 7 are held fast by means of revolving bar clamps 8 pivoted on rivets 9 extending through the tie body member 1. The rail engaging ends of the 50 bar clamps are indicated by the numeral 10, and these are slightly inclined upward to allow them to slide over the rail bases 7. To insure that these members will move into place easily, all the corners and the edges 55 are rounded off as is indicated plainly in Figs. 1 and 2. The ends of the bar clamps 8, opposite the rail engaging ends 10, comprise spring locking members 11, which slant at a slight angle upward to afford a 60 more positive spring action. The ends of these last mentioned members are narrowed and taper down to an end lug 12 which is bent sharply downward to form a locking means for engagement with a depression 13 in the tie body 1. This taper insures the

proper flexibility and saves considerably in the cost of production by economizing in material.

In the modification shown in Fig. 3, the portion of the tie body 1, designed to contact with the ground, is provided with cross plates 14, which become embedded in the soil and prevent the creeping of the tie in a direction laterally of the track. These cross plates 14 may be formed on the tie body by any desired method and their process of manufacture constitutes no part of this invention.

As will be apparent from the specification there is no necessity for the use of wedges or blocks of wood or metal to insure the proper gripping of the holding clamps against the rail bases as has been the practice in the prior art. The holding clamps are constructed to accurately engage the rail bases and no other holding means need be used with our device for the inside of the rail.

One of the greatest advantages of our invention lies in the simplicity of construction. There are no auxiliary parts to be lost in the mud; the laying or the removal of the track requires no special tools; there are few parts to become out of order and repair is easily and quickly effected.

What we claim is:

1. In a metallic railway tie, the combination of a metallic tie body of substantially channel beam cross section adapted to engage the earth to prevent slipping of the tie in the direction of the track, holding clamps bent up from the ends of the channel beam of the tie body itself to clamp the outside of the rail bases, and revolving bar clamps with rounded ends to engage the inside of the railbases, with means attached to the tie body to prevent slipping of the tie laterally of the direction of the track.

2. In a metallic railway tie, the combination of a metallic tie body of substantially channel beam cross section adapted to engage the earth to prevent slipping of the tie in the direction of the track, holding clamps bent up from the ends of the tie body to engage and clamp the outside of the rail bases, and revolving bar clamps having rounded rail engaging ends to engage the inside of the rail base, the other ends being upwardly slanting and tapered, with lugs bent from the body of the clamp for engagement with depressions in the tie body to lock the clamp is position.

3. In a metallic railway tie, the combination of a metallic tie body of substantially channel beam cross section adapted to engage the earth to prevent slipping of the tie in the direction of the track, and holding clamps bent up from the ends of the tie body to clamp the outside of the railbases, with revolving bar clamps having rounded rail

engaging ends to engage the inside of the railbases, the other ends of said bar clamps being provided with lugs bent from the body of the clamp which are spring pressed by the natural spring of the metal of the bar into engagement with a depression in the tie body to hold the bar against rotation.

4. In a metallic railway tie, the combination of a metallic tie body of substantially 10 channel beam cross section adapted to engage the earth to prevent slipping of the tie in the direction of the track, holding clamps bent up from the ends of the tie body to accurately engage and clamp the outside of 15 the railbases, and revolving bar clamps having rounded rail engaging ends to engage the inside of the railbases, and having their other ends tapered and provided with lugs bent from the body of the clamp, with means 20 attached to the tie body to prevent slipping of the tie laterally of the direction of the track.

5. In a metallic railway tie, the combination of a metallic tie body of substantially 25 channel beam cross section adapted to engage the earth to prevent slipping of the tie in the direction of the track, and holding

clamps bent up from the ends of the tie body to accurately engage and clamp the outside of the railbases, with revolving bar clamps 30 having rounded rail engaging ends to engage the inside of the railbases, the other ends of said bar clamps being provided with lugs bent from the body of the clamp which are 35 spring pressed by the natural spring of the metal of the bar into engagement with a depression in the tie body to hold the bar against rotation.

6. In a metallic railway tie, the combination of a metallic tie body of substantially 40 channel beam cross section adapted to engage the earth to prevent slipping of the tie in the direction of the track, holding clamps bent up from the ends of the tie body to clamp the outside of the railbases, and revolving bar clamps to engage the inside of 45 the railbases, with cross plates formed within the channel groove of the base of the tie to prevent slipping of the tie laterally of the direction of the track. 50

In testimony whereof, we affix our signatures.

WILLIAM B. GATEWOOD.
VICTOR P. DALMAS.
